(57) **CLAIM**

The ornamental design for a shelf assembly for handbag display, as shown and described.

DESCRIPTION

FIG. 1 is a front elevation view of my new design;
FIG. 2 is a top plan view thereof;
FIG. 3 is a bottom plan view thereof;
FIG. 4 is a right side elevation view thereof;
FIG. 5 is a left side elevation view thereof; and,
FIG. 6 is an enlarged cross-sectional view taken along line 6-6 of FIG. 2 and showing essential details of the new design.
The broken lines in FIGS. 1, 2, 3 and 6 represent features that form no part of the claimed design.
